CLAIM

I claim the original and ornamental design for the shoe sole,
as shown and described.

DESCRIPTION

FIG. 1 is a top plan view of a shoe sole showing the present invention;

FIG. 2 is a front elevational view thereof;

FIG. 3 is a bottom plan view thereof;

FIG. 4 is a rear elevational view thereof;

FIG. 5 is a right side elevational view thereof; and,

FIG. 6 is a left side elevational view thereof.
